COMBUSTION-ENGINE.

1,351,718.

Specification of Letters Patent. Patented Aug. 31, 1920.

Application filed June 22, 1915. Serial No. 35,498.

To all whom it may concern:

This specification bears witness that I, WILLIAM T. PRICE, a subject of the King of Great Britain, residing at 129 Sickels avenue, New Rochelle, N. Y., have invented the following-described Improvements in Combustion-Engines.

The purpose of the structure incorporating these improvements is to avoid the escape into the surrounding atmosphere of smoke or combustion products or lubricating oil at the crank end of the cylinder and to adapt the engine to consume the objectionable gases which would normally find egress at this region. These objects are accomplished by simple mechanism, capable of application to various types of engines, at small expense and without interference with other parts, and which provides a constantly open communication between the crank space inclosure and the atmosphere, allowing the air to be moved back and forth therein by the to and fro motion of the piston but without opportunity for the escape of smoke except to the engine itself or to some other suitable place of disposal.

In the accompanying drawings forming a part hereof:

Figure 1 is a longitudinal section through a horizontal four-cycle engine (although any other cycle engine may be used) embodying the invention, the arrows indicating the direction of movement on the firing stroke.

Fig. 2 is a cross-section on the line 2—2 of Fig. 1; and

Figs. 3, 4 and 5 are diagrammatic views, representing the sequence of operation on the compression, exhaust and intake strokes respectively.

The invention is designed more especially for stationary horizontal four-cycle and two-cycle engines, and the drawing illustrates a single four-cycle cylinder engine of this character, but without limitation thereto.

The cylinder marked 6 is carried on a bed frame 7, resting on a foundation 8, and at its inner end is provided with a combustion air valve 9, an exhaust valve 10 controlling the exhaust passage 11, a starting air valve 12, between the two and in line with the axis of the piston, and a fuel valve 13 cross-wise of such axis. The valves as thus arranged control a combustion space 14 between them which in turn communicates with the interior of the cylinder proper. In this par-

ticular type of engine the fuel valve sprays liquid fuel into a body of air compressed in the space 14 and the products of combustion expand against the piston 17 producing motion of the latter in the usual way. As 60 already indicated, however, the design and type of the engine are not material to this invention except as hereinafter specified. In this, as in other types of engines, there is some leakage of combustion gases past the 65 piston on the firing stroke, which leakage naturally increases with the wear of the piston rings and there is also some burning of the cylinder lubricating oil from the heat of the combustion on the surface of the piston 70 and from engine lubricating oil splashed into the hot interior of the piston resulting in the escape at the crank case of ill-smelling and more or less poisonous vapors which contaminate the air of the engine room. Furthermore, lubricating oil suspended in the 75 air in fine particles is carried out into the room with the displaced air and gases.

According to this invention, the crank 15 and its connecting rods 16 are inclosed in 80 a casing formed in part by the engine bed 7 beyond the cylinder and the crank shaft journals and in part by a cover 18 fitted to such bed and connected with the outer end of the cylinder by a hood 19. The mode 85 of operation, as hereinafter explained, permits the cover 18 and associated inclosing parts to be made of very light sheet metal, without tendency toward excessive bulging from interior pressures. As shown in Fig. 90

2, the engine bed is a casting having upstanding hollow side walls 20, on which the upright side walls 25 of the cover 18 are supported by means of the iron clips 21. The rearmost wall of the cover rests on an 95 end wall 22 of the bed. The various parts are desirably united in such manner as to insure substantially tight joints while permitting the removal of the casing when necessary. The two spaced sheet metal 100 walls 23 and 24 forming the transverse members of the cover are each curved approximately concentric to the crank shaft and held in proper relative position by appropriate angle connections to the vertical 105 side walls 25, as indicated in Fig. 1. The outer wall 23 has an opening 27 formed therein at about the top of the curvature in the present case, and the space between the two walls 23 and 24 forms a passage 26 110

which connects this opening with a second opening 28 through or around the rear end of the wall 24 and with two other openings 29 at the front end of the said inner wall. 5 These openings 29 are formed by an interposed U shaped baffle wall 30 embracing the space in which the connecting rod 16 travels, such wall being connected to the cover walls 23 and 24 in suitable manner as 10 indicated in Figs. 1 and 2. The crank space of the engine is thus put into indirect communication by means of two relatively remote openings (28 and 29) with the surrounding outside air, such communication 15 being constantly open as indicated. This arrangement of ports and passage provides a relatively long path for the contents of the casing to follow in order to escape to the engine room and is effective in confining 20 the smoke and gases, although it permits the air therein to surge back and forth as the piston reciprocates. A general flow of air is induced in the inclosed crank space sufficient to keep the net movement inward, 25 by means of a connection between the crank case and the air valve 9. This connection is formed by a passage 31 communicating with the said crank space through two lateral openings on either side of the connecting rod indicated at 32 and also communicating with an out-take passage 33, which is connected by a pipe 34 with the housing of the air intake valve 9. The relative vacuum produced by the suction of the piston 17 30 draws air, and such smoke as it may contain, through this passage and into the cylinder, whence it is discharged to the exhaust in due course. The opening 35, provided in the passage 31 and the silencing intake 35 pipe 36 with its slotted openings 37 admits more or less outside air to the passage 31 and may be gaged so that the general movement through the crank case and toward the intake valve shall be as strong as may be 40 necessary.

In operation and by reason of the length of the crank space passage 26, no smoke issues from the latter on the firing stroke. A small portion of the gas may pass through 50 opening 32 and from passage 31 some may be displaced downward into intake pipe 36, but by reason of the length of this pipe none escapes through the openings 37. On the inward or exhaust stroke air is drawn 55 into the passage 26 and part is drawn back through passage 32, 31 and upward through intake pipe 36. During the next stroke, *i. e.*, the suction stroke of the engine, the air valve 9 being open, the contents of the crank 60 space move through passage 32 toward such valve and air is drawn in freely through intake pipe 36. During this operation there may be comparatively little movement of air through the passage 26 depending upon 65 the relative proportions of the various pas-

sages. During the compression stroke air is again drawn in the crank space passage and on the following stroke the cycle is repeated.

While the preferred form of my invention 70 has now been described in detail, it will be understood that numerous changes and modifications are possible and within its scope. Thus, for example, the number of walls 23 and 24 and the length of the passage between them may be changed or increased and other means may be employed for producing the inward advance of the surging currents therein.

Intake pipe 36 and opening 35 may be 80 entirely eliminated thus causing all the air for combustion to be drawn in through opening 27 and passages 26 and moreover I do not confine my invention entirely to internal combustion engines as the cover may 85 be used to advantage on air compressors and other machines of the single acting type.

What is claimed as new is:

1. In an internal combustion engine, cylinder provided with an admission port, 90 combined with a crank inclosure communicating with the outer end of the cylinder and formed with an intervening space affording a constantly open passage communicating at remote points on the one hand with the interior of the inclosure and on the other hand with the atmosphere, and means for transferring air from the interior of the inclosure to said admission port.

2. In an internal combustion engine, the combination with a cylinder containing a piston, intake and exhaust valves operating on a four-stroke cycle, of an inclosure at the crank end of the cylinder having a relatively long circuitous communication with the atmosphere, and a passage leading from the interior of said inclosure to said air intake valve.

3. In an internal combustion engine, a crank inclosure having double walls with offset ports communicating respectively with the crank space and with the atmosphere and affording a circuitous passageway constantly open to oscillatory air movement.

4. In an internal combustion engine, the combination of a cylinder, a crank space cover having spaced walls provided with openings so arranged as to afford a relatively long passageway between said space and the atmosphere, said passageway being 115 constantly open with respect to air movement in both directions, and a means for withdrawing the gaseous contents of said space to cause a net flow through said communication toward the interior of said space.

5. In an internal combustion engine, a horizontal cylinder having an intake at its inner end, a bed frame containing an air passage leading to said intake, and a crank inclosure at the outer end of the cylinder 120

having a constantly open communication with the atmosphere and also an outlet to the said passage.

6. In an internal combustion engine, a cylinder having an air intake port at its inner end, a crank inclosure at the outer end of the cylinder having a passage space intervening between its interior and the atmosphere, a passage beneath the cylinder connecting the interior of the crank inclosure with said air intake port, and means for admitting air to said intake port independently of the crank inclosure, through a passage of substantial length.
10. In an internal combustion engine, the combination with a horizontal cylinder and piston, of a crank space inclosure comprising a cover constituted of spaced arched walls forming a passageway having an opening to the atmosphere toward the top and openings to the interior of the crank space at or near the ends.
15. In an internal combustion engine, a horizontal cylinder having air admission means at its inner end, a crank space inclosure comprising spaced walls forming a passageway open at or near the top to the atmosphere and at lower points having openings to the crank space, and a passage for conducting the contents of the crank space to the said air admission means.

20. In an internal combustion engine, the combination with a cylinder, a double-walled inclosure for the crank thereof having a passage constantly open to air movement in both directions, curved concentrically to the crank shaft, and through which

the interior of the inclosure is in communication with the atmosphere.

25. In an internal combustion engine, the combination with the engine air intake port and a crank inclosure normally open to atmosphere and provided with an air passage leading to said port, of an auxiliary air inlet for leading outside air to said air passage.

30. In an internal combustion engine, the combination with the engine air intake port, a crank inclosure having a constantly open circuitous communication with the atmosphere and an air passage connecting such inclosure with the intake port, of an auxiliary air inlet provided with a series of slits through which outside air may pass to said air passage.

35. In an internal combustion engine, the combination with the air intake port thereof, a crank inclosure having open communication with atmosphere, a constantly-open passage through which air from the inclosure is drawn to the said port, and a constantly open auxiliary air inlet for admitting outside air to said passage, the said passages being arranged and adapted to prevent escape of the crank inclosure odors or gases into the surrounding atmosphere.

40. In testimony whereof, I have signed this specification in the presence of two witnesses.

WILLIAM T. PRICE.
